UNITED STATES PATENT OFFICE.

FREDERICK W. CARLSON, OF HELENA, MONTANA.

CURTAIN-ROD.

1,060,426.

Specification of Letters Patent. Patented Apr. 29, 1913.

Application filed November 1, 1912. Serial No. 729,112.

To all whom it may concern:

Be it known that I, FREDERICK W. CARLSON, a citizen of the United States, residing at Helena, in the county of Lewis and Clark 5 and State of Montana, have invented certain new and useful Improvements in Curtain-Rods, of which the following is a specification, reference being had therein to the accompanying drawing.

10 This invention relates to curtain poles, and has for its object the production of a simple and efficient pole which will support the curtain in such a manner as to prevent the curtain from sliding back and forth 15 when it is not so desired.

Another object of this invention is the production of a simple and efficient curtain pole whereby the curtain supporting pins may be freely moved back and forth upon 20 the pole under normal conditions, and the curtain supporting portions will be held against accidental removal from the pole.

In the drawings:—Figure 1 is a small perspective view of the portion of the pole 25 used in connection with the present invention. Fig. 2 is a bottom plan view of a portion of the pole showing the supporting bracket attached thereto. Fig. 3 is a section taken on the line 3—3 of Fig. 2. Fig. 30 4 is a bottom plan view of one end of the pole. Fig. 5 is a transverse section through the pole showing the supporting bolts passing therethrough. Fig. 6 is a sectional view 35 through the pole showing the modified form of supporting pole used in connection with the present device.

By referring to the drawings by numerals, it will be seen that the pole 1 comprises an elongated body having a longitudinally extending slot 2 formed upon its lower face, which slot extends throughout the entire length of the pole 1. The side edges of the slot 2 are provided with notched portions 3 near one end thereof for facilitating the 40 placing of the curtain supporting knobs 4 into the slot 2. The knobs 4 comprise an enlarged head 5 which is in the form of a ball and a depending lug 6 is formed upon the lower edge of the ball 5 being square in 45 cross-section. An aperture 7 is formed in the lug 6 through which is adapted to pass the curtain supporting hooks 8. It will be seen that by having the lugs 6 formed square in cross-section, the balls will be held 50 against rotation within the pole 1 thereby at all times holding the curtain in its cor-

rect position and preventing the curtain supporting hooks or pins 8 from twisting.

A bracket 9 engages each end of the pole 1 as illustrated in Fig. 1 and is so positioned 60 as to overhang the notches 3 for preventing the accidental removal of the balls 5 from the tube 1. The brackets 9 are provided with tubular portions 10 which tubular portions receive the ends of the pole 1, and these brackets are provided with laterally 65 extending feet 11 for facilitating the attachment of the bracket to a support.

Supporting bolts 12 pass transversely through the pole 1 as illustrated in Fig. 5, 70 and these bolts 12 are provided with threaded ends 13 which threaded ends are adapted to be threaded into a support 14 for supporting the pole 1 in an operative position. A binding nut 15 is threaded upon the 75 bolt 12 and engages the pole 1 as indicated in Fig. 5. The outer clamping nut 16 is threaded upon the outer end of the bolt 12, and it will therefore be seen that the pole 1 will be clamped between the nuts 15 and 80 16. The pole is, as illustrated in Fig. 5, thinner at its lower edge than upon the top 17, and since the pole 1 is clamped between the nuts 15 and 16 it will be seen that by tightly threading the nut 16 upon the bolt 85 12, the edges 18 of the slot 2 may be firmly clamped around the lug 6 so as to hold the ball 5 against longitudinal movement within the pole 1. A groove 19 is formed upon the outer end of the bolt 12 for allowing 90 the bolt to be threaded into the support 14.

As illustrated in Fig. 6, the bolt 12 may be provided with a squared shank portion 20 for allowing a wrench to grip the same 95 for facilitating the threading of the bolt 12 into a support. It will be seen that the nuts 21 and 22 will firmly clamp the pole 1 upon the bolt 12 and hold the same against longitudinal movement upon the pole.

From the foregoing it will be seen that a 100 very efficient and durable pole has been produced whereby the curtain supporting hooks may be easily attached thereto.

What I claim is:—

1. A pole of the class described comprising a pole provided with a longitudinally extending slot upon its lower face, knobs working in said pole and provided with depending squared portions working in said slot, supporting brackets for said pole, supporting rods passing through said pole and engaging a support, nuts threaded upon 105 110

said rod upon each side of said pole, and said nuts being adapted to be adjusted for firmly clamping the side edges of said slot around said knobs for holding said 5 knobs against longitudinal movement relative to said pole.

2. A device of the class described comprising a pole provided with a longitudinally extending slot, knobs working in said 10 pole and provided with depending portion working in said slots, supporting bolts passing transversely through said pole and pro-

vided with a squared shank intermediate its ends for facilitating the threading of said rod into a support, and clamping nuts positioned upon each side of said pole for firmly holding said pole in a set position upon said rods. 15

In testimony whereof I hereunto affix my signature in presence of two witnesses.

FREDERICK W. CARLSON.
